PORTABLE DUSTER FOR INSECTICIDES OR THE LIKE

William D. Love, Jr., Orinda, Calif.
(2002 Davis St., San Leandro, Calif.)

Filed Oct. 11, 1960, Ser. No. 62,445

Term of patent 14 years

(Cl. D31—3)

F i g. 2

F i g. 4

F i g. 3

FIGURE 1 is a rear perspective view taken from the top and one side of a portable duster for insecticides or the like embodying my new design;

FIGURE 2 is an elevational view of the opposite side thereof, a portion of the nozzle being broken away for convenience of illustration;

FIGURE 3 is a rear elevational view thereof; and
FIGURE 4 is a front elevational view thereof.

I claim:

The ornamental design for a portable duster for insecticides or the like, substantially as shown.
